George Scott, of New York, N.Y.

Letters Patent No 1883-Dated Jan'y 13th 1864

Design for a Bottle.

The schedule referred to in these Letters Patent and making part of the same.

To all whom it may concern:

Be it known that I, George Scott, of the City, County, and State of New York, have produced a new and ornamental Design for a Cottage Bottle; and I do hereby declare that the following is a full, clear, and exact description of the same, reference being had to the accompanying drawing forming part of this specification, in which -

Figure 1 represents a perspective view of my bottle.

Figure 2, is a horizontal section of the same.

Similar letters of reference in both views indicate corresponding parts.

The object of this invention is to produce a bottle in imitation of a cottage the sides of which are protected by clapboards and its corners by corner pieces similar to those used for the protection of ordinary cottages. It is provided with a door in one side and with windows in the others and its roof is formed so as to imitate an ordinary shingle roof from the centre of which the neck of the bottle rises in imitation of a chimney.

To enable others skilled in the art to make and use my invention, I will proceed to describe it.

Figure 1 represents a bottle made of glass or other suitable material. The sides *a* of the body of this bottle are covered with a series of ribs *b*, formed in imitation of the clapboards used for the protection of ordinary cottages and the corners *c*, are formed in imitation of the corner pieces used to protect the corners in ordinary cottages. The clapboards *b*, and corner pieces *c*, extend from the bottom of the bottle up to the eaves

d. of the roof like top B. This roof is made in the form of a four sided pyramid and its sides are covered with projections e. which give to it the appearance of an ordinary shingle roof. From the apex of the roof B. rises the neck C, which represents the chimney of the cottage.

One side of the bottle is provided with a door e, hung on hinges f. in the door frame g. which appears to be inserted into the side of the cottage in the usual manner. A knob h. and key hole i. completes the door and imparts to it a perfect resemblance to a real door.

Two of the other sides of the cottage are provided with windows j. the casings k. of which are inserted into said sides in perfect imitation of those of real window casings inserted into the clapboarded sides of a cottage. The space between the casing of each window is divided off into a series of squares to represent the panes of a real window. That side of the bottle opposite the door and representing the rear side of the cottage is without either door or window and it is intended to afford room for the label or etiquette or for the name of the manufacturer and of the contents of the bottle, which may be cast in the glass or other material from which the bottle is made.

What I claim as new and desire to secure by Letters Patent is the Design for a bottle as shown and described.
